[57] CLAIM

The ornamental design for the container dome, as shown and described.

DESCRIPTION

FIG. 1 is a perspective view of a container dome embodying my new design;

FIG. 2 is a top plan view of the container dome of FIG. 1;
FIG. 3 is a front elevational view of the container dome of FIG. 1, the rear, left and right side elevational views being identical;

FIG. 4 is a bottom plan view of the container dome of FIG. 1; and,

FIG. 5 is a perspective view of a container having the container dome of FIG. 1.

The broken line showing in FIG. 5 of the container finish and sidewall is for illustrative purposes only and forms no part of the claimed design.
